UNITED STATES PATENT OFFICE

OSCAR J. SUNDSTRAND, OF ROCKFORD, ILLINOIS, ASSIGNOR TO SUNDSTRAND CORPORATION, OF WILMINGTON, DELAWARE, A CORPORATION OF DELAWARE

PAPER CARRIAGE

Application filed December 17, 1928. Serial No. 326,646.

This invention relates to paper carriages such as are used in typewriters and bookkeeping machines. It relates more particularly to a paper carriage provided with several aligned platen-sections, and has special reference to means whereby an intermediate section may be rotated independently of the other sections, and means whereby an intermediate section may be rotated synchronously with one of the other sections by means such as the usual finger wheel, and by means of an injecting and ejecting mechanism, and by means operable in the regular operation of the machine.

15 In the accompanying drawing,

Figure 1 is a fragmental longitudinal central section through the left-hand end platen-section.

Fig. 2 is a longitudinal sectional view of the right-hand end platen-section.

Fig. 3 is a fragmental front view of the paper carriage.

Fig. 4 is a perspective view of a locking shoe comprised in the construction.

25 Fig. 5 is a perspective view of a member in the nature of an arm.

Fig. 6 is a fragmental sectional view of the left-hand end platen-section.

Fig. 7 is a section on line 7—7 of Fig. 3.

20 Fig. 8 is a fragmental view of a ratchet mechanism.

Fig. 9 is a detail view of the arm 18 and the pawl 39—40 carried thereby. The pawl 17 is omitted for the sake of clearness.

35 The present embodiment of the invention comprises a platen formed in three aligned sections A, B and C. We may assume that the section A is to be used for the tally web, the section B for the ledger sheet, and the section C for the statement, although this particular arrangement of the work-pieces is not important.

The section A has fixed thereto a tubular shaft 1 which is supported in a bearing bushing 2 that is fixed to the end plate 3 of the paper carriage. The means for manually turning the platen-section A comprises a finger wheel 4 which is rigidly secured to the tubular shaft 1.

50 The platen-section B is fixed to a shaft 5,

the right-hand portion of which is rotatably supported within the tubular shaft 1. The means for manually turning the platen-section B comprises a finger wheel 6 that is rigidly secured to the right-hand end of the shaft 5.

The platen-section C is rotatably supported in the following manner: The right-hand end of the platen-section C has a bearing 7 (Fig. 1) which is rotatably supported upon the left-hand portion of the shaft 5. The left-hand end of the platen-section C has fixed thereto a bearing sleeve 8 which is mounted upon a tubular shaft 9, the sleeve being fixed to the shaft 9 by means of set screws 10. The shaft 9 is rotatably supported in a bushing 11 that is fixed to the left-hand end plate 12 of the paper carriage. The left-hand end of the shaft 5 is reduced in diameter and is rotatably supported within the inner end of the sleeve 8. The means for manually rotating the platen-section C comprises a finger wheel 13 having a sleeve 14 which is fixed to the tubular shaft 9 by means of set screws 15.

The means for imparting line-space movements to the platen-section A in the operation of the machine comprises a ratchet wheel 16 (Fig. 1) which is fixed to the tubular shaft 1. A pawl 17 is pivoted to the lower end of an arm 18, the upper end of said arm being pivoted to the paper carriage at 19. A tension spring 20 stretched between the pawl 17 and the arm 18 normally holds the pawl in engagement with the ratchet wheel. 21 is a stationary cam fixed to the end plate 3 and arranged to be engaged by a stud 22 on the pawl 17 as the pawl completes its forward stroke. The arm 18 is arranged to be swung forward during the return stroke of the main operating handle (not shown) by the means usually employed in machines of this character, or in any preferred manner. The only portion of said means herein shown is a rod 23, the right-hand end of which is connected to the lower end of the arm 18.

45 Detent means of the usual character, as, for example, a spring arm carrying a roller engaging the teeth of the ratchet wheel, is preferably provided to hold the platen-section 95 100 104

tion A against casual rotation and to complete the line-space movement initiated by the pawl 17. For the sake of clearness, such detent means has been omitted from the drawing.

The means for imparting line-space movements to the platen-section C in the operation of the machine may be and preferably is substantially identical with that described 10 in connection with the platen-section A. 24 is a ratchet wheel yeldingly connected to the tubular shaft 9 and arranged to be engaged by a pawl 25 pivoted on the lower end of an arm 26 which is similar to the arm 15 18 and is mounted to swing upon the axis 19. The lower end of the arm 26 is connected to the transverse rod 23 so that the arms 18 and 26 swing in unison.

Means is preferably provided for imparting 20 rapid rotative movements to the platen-sections B and C for quickly bringing the ledger sheet and the statement to approximate printing position and for quickly ejecting said sheets from the machine. Said injecting and ejecting means may be of any 25 preferred construction, the only portion of such means herein shown being a pinion 27 which is rigidly connected to the right-hand portion of the shaft 5 for turning the platen-section B, and a similar pinion 28 which is rigidly secured to the tubular shaft 9 for rapidly rotating the platen-section C.

The platen-section B is arranged to be reasonably connected to the platen-section C so 35 as to rotate therewith. The means herein shown for thus uniting the two platen-sections B and C comprises a screw 29 (Fig. 6), the stem 30 of which is rotatably supported in the tubular shaft 9. The stem 30 has a 40 knurled head 31 by means of which it may be turned. The screw 29 is guided within an axial opening 32 in the shaft 5 and is arranged to engage screw-threads 33 formed in said shaft. At the outer end of the screw 29 45 the stem 30 is tapered as at 34. When the screw 29 is turned into engagement with the threads 33, the tapered portion 34 engages a semi-circular shoe 35 which is mounted in a recess 36 formed in that portion of the shaft 50 5 which is rotatably supported in the inner end of the sleeve 8. When the screw 29 is turned into engagement with the threads 33, the tapered portion 34 forces the shoe 35 radially outward into clamping engagement with 55 the sleeve 8, whereby the shaft 5 is fixed to the sleeve 8, and the sections B and C united.

An expansive spring 37 surrounding the outer portion of the stem 30 bears at one end against the head 31 and at its other end 60 against the outer end of the tubular shaft 9. When the screw 29 is turned out of engagement with the threads 33 the spring 37 moves the screw toward the left and holds it out of engagement with the threads 33. The action 65 of the spring 37 is limited by contact of a

stop 37^a on the stem 30 with the inner end of the shaft 9.

Means is provided for imparting line-space movements to the middle platen-section B in the regular operation of the machine. Said 70 means comprises a toothed wheel 38 which is fixed to the right-hand portion of the shaft 5 and is arranged to be engaged by a reciprocating toothed member. In this instance, said toothed member is in the form of a hardened 75 bar or block 39 which is fixed to a member 40 (Fig. 5) in the nature of an arm pivoted to the arm 18. The member 40 is pivoted upon a stud 41 which is fixed to the arm 18. A tension spring 42 is stretched between the member 40 and a lug 42^a on the arm 18 and tends to hold the toothed block 39 in contact with the toothed wheel 38. Near the end of its forward stroke, the toothed bar 39 is moved 80 downwardly out of engagement with the wheel 38 by reason of the engagement of a pin 43 on the member 40 with a cam 44 fixed to the end plate 3.

By reason of the fact that the means for turning the middle platen-section B in the 90 regular operation of the machine must be located at the right-hand side of the finger wheel 4 and the injector and ejector pinion 27, the toothed wheel 38 is necessarily located at a considerable distance from the end plate 3 of the paper carriage. It is therefore impracticable to provide, in connection with the toothed wheel 38, means such as is usually provided in connection with a line-space wheel for completing the movement initiated by the line-space pawl. For this reason the wheel 38 has been provided with relatively fine teeth, the teeth of the block 39 being of the same character. There being practically no lost movement between the ratchet block 39 and the ratchet wheel 38, said block is adapted to begin turning the wheel immediately upon the beginning of a forward stroke of the arm 18. I am thereby enabled to obtain sufficient rotative movement of the wheel 38 to turn the platen-section B a full line space without employing means such as is used in connection with the ratchet wheels 16 and 24 for completing the line-space movements of the platen-sections A and C. 105

It will be seen that each platen section may be manually rotated independently of the others; that the middle section and the left-hand section may be rapidly rotated to inject and eject the work-pieces; and that all the sections may be simultaneously line-spaced in the regular operation of the machine. 110

The ledger section B and the statement section C need to be relatively rotatable after the ledger sheet and the statement have been fed into the machine, as the lines to be written upon will ordinarily be at different distances from the upper edges of the respec- 115

tive sheets. The construction herein shown permits of such relative rotation by means of the finger wheels 6 and 13. After the lines on said sheets have been alined the platen sections B and C may be simultaneously line-spaced by means of the ratchets 24 and 38, or they may be connected, if desired, by means of the clamping means 35, so as to be simultaneously rotatable by means of the finger wheel 13.

10 The clamping means 35 finds its greatest usefulness when it is desired to print upon a sheet of such width that both of the platen sections B and C must be used.

15 As will be understood, the tally tape remains in the machine while entries are being made upon a succession of pairs of ledger sheets and statements, and is regularly line-spaced by means of the pawl and ratchet 20 16-17.

I claim as my invention:

1. A platen comprising three alined sections, each end section having an outwardly extending tubular shaft, finger wheels secured to said shafts, a shaft to which the middle section is rigidly secured, one end of said shaft being rotatably mounted in one of said tubular shafts and having a finger wheel at its outer end, the opposite end of 30 the shaft of said middle section being rotatably supported in the adjacent end section, releasable means for connecting the last-mentioned end of the shaft of the middle section to said adjacent end section, ratchet 35 mechanism connected to each of said tubular shafts for imparting line-spaced movement to the respective end sections, and ratchet mechanism connected to the first-mentioned end of the shaft of the middle section for imparting 40 line-space movement to the middle section.

2. A platen comprising three alined sections, each end section having an outwardly extending tubular shaft, finger wheels secured to said shafts, a shaft to which the middle section is rigidly secured, one end of said shaft being rotatably mounted in one of said tubular shafts and having a finger wheel at its outer end, the opposite end of the shaft of said middle section being rotatably supported in the adjacent end section, ratchet 50 mechanism connected to each of said tubular shafts for imparting line-space movement to the respective end sections, ratchet mechanism connected to the first-mentioned end of the shaft of the middle section for imparting line-space movement to the middle section and means connecting all of said ratchet mechanism for simultaneous actuation.

3. A platen comprising three alined sections, each end section having an outwardly extending tubular shaft, a shaft to which the middle section is rigidly secured, one end of said shaft being rotatably mounted in one of said tubular shafts and having a finger 60 wheel at its outer end, the opposite end of

the shaft of said middle section being rotatably supported in the adjacent end section, ratchet mechanism connected to each of said tubular shafts for imparting line-space movement to the respective end sections, ratchet mechanism connected to the first-mentioned end of the shaft of the middle section for imparting line-space movement to the middle section and means connecting all of said ratchet mechanisms for simultaneous actuation. 70 75

4. The combination of a platen comprising two alined sections, one of the sections having a tubular shaft and an internal bearing member and the other section having a shaft which is rotatably supported in said bearing member, and releasable means for rigidly connecting the end of the second shaft to said bearing member to lock said sections together, said means including a screw having a stem extending through the tubular shaft, said screw being adapted to engage a threaded portion of the second shaft, and a shoe loosely mounted within a recess in the second shaft, said stem having a tapered portion arranged to press said shoe radially outward against the bearing member when the screw is engaged with said threaded portion. 80 85 90

5. The combination of a platen comprising two alined sections, one of the sections having a tubular shaft and an internal bearing member and the other section having a shaft which is rotatably supported in said bearing member, and releasable means for rigidly connecting the end of the second shaft to said bearing member to lock said sections together, said means including a screw having a stem extending through the tubular shaft, said screw being adapted to engage a threaded portion of the second shaft, and a locking member within the bearing member, said stem being arranged to press said locking member against the bearing member when the screw is engaged with said threaded portion. 95 100 105 110

6. The combination of a platen comprising three alined sections, one of the end sections having a tubular shaft and an internal bearing member and the middle section having a shaft which is rotatably supported in said bearing member, and releasable means for rigidly connecting the end of the second shaft to said bearing member to lock said end section and the middle section together, said means including a screw having a stem extending through the tubular shaft, said screw being adapted to engage a threaded portion of the second shaft, and a locking member within the bearing member, said stem having a portion arranged to press said locking member against the bearing member when the screw is engaged with said threaded portion. 115 120 125

7. The combination of two alined platen. 130

sections, means for rotatably supporting said sections, said means including a tubular shaft secured to one section and a shaft secured to the other section and lying within the tubular shaft, a line-space ratchet wheel secured to the tubular shaft, a line-space ratchet wheel secured to the other shaft, two pawls, one for each of said ratchet wheels, and means for simultaneously actuating said pawls, said pawls being supported for independent pivotal movement.

8. The combination of two alined platen-sections, means for rotatably supporting said sections, said means including a tubular shaft secured to one section and a shaft secured to the other section and lying within the tubular shaft, a line-space ratchet wheel secured to the tubular shaft, a line-space ratchet wheel secured to the other shaft, two pawls, one for each of said ratchet wheels, the second-mentioned line-space wheel having relatively fine teeth, and the corresponding pawl having a series of relatively fine teeth adapted and arranged to engage the second-mentioned wheel with approximately no lost motion, and means for actuating said pawls.

9. The combination of two alined platen sections, means for rotatably supporting said sections, said means including a tubular shaft secured to one section and a shaft secured to the other section and lying within the tubular shaft, a line-space ratchet wheel secured to the tubular shaft, a line-space ratchet wheel secured to the other shaft, a finger wheel secured to the tubular shaft at a point between the line-space wheels, two pawls, one for each of said ratchet wheels, and a single means for simultaneously actuating both pawls.

10. The combination of a platen comprising a series of three alined sections, all held against endwise movement relatively to each other, means operable from one end of the series for releasably locking the middle section to one of the end sections and means operable from the other end of the series for independently rotating the middle section and the other end section.

11. A paper carriage for bookkeeping machines or typewriters having three alined platen-sections held against endwise movement relative to one another, an injecting and ejecting pinion and a line-space gear fixed to one of the end sections and located at one end of the series of platen-sections, and an injecting and ejecting pinion and a line-space gear fixed to the middle section and located at the other end of the series of platen-sections.

12. A paper carriage for bookkeeping machines or typewriters having three alined platen-sections held against endwise movement relative to one another, an injecting and ejecting pinion fixed to one of the end sec-

tions, an injecting and ejecting pinion fixed to the middle section, and means to connect the last-mentioned end-section to the middle section to cause said sections to rotate as a unit independently of the second end section. 70

13. A paper carriage for bookkeeping machines having a statement platen-section, a ledger-sheet platen-section and a tally platen-section, said platen-sections being axially alined and normally rotatable independently 75 of each other, and three line-space ratchet mechanisms each for rotating one of said platen-sections, all of said ratchet mechanisms being connected together for simultaneous actuation.

14. A paper carriage for bookkeeping machines having three alined platen-sections, three line-space ratchet mechanisms, each for rotating one of said platen-sections, an actuating rod extending lengthwise of the carriage and connecting two of said mechanisms for simultaneous actuation, and a driving connection between the third line-space mechanism and one of the others. 80

In testimony whereof, I have hereunto af- 90 fixed my signature.

OSCAR J. SUNDSTRAND.
